1

This invention is a method for concentrating carotene from palm oil by heating the palm oil to bring about a split of carotene complexes and then concentrating the carotene by solvent extraction with a low boiling solvent under paracritical conditions.

Carotenes have an important nutritional function as pro-vitamin A, i. e. some of them being convertible by the human system into vitamin A. One of their principal commercial sources is palm oil from which they are concentrated for nutritional and medicinal purposes.

One method for concentrating carotenes from oils such as palm oil has been disclosed and patented, U. S. P. No. 2,432,021 of H. B. Larner, issued on December 2, 1947. Briefly, the method there employed was to countercurrently contact the oil with propane (or a similar solvent) under elevated temperature and pressure conditions (i. e. in the paracritical range) to cause the solvent and oil mixture to form two phases. Although both phases contain solvent, the lighter and heavier phases are referred to as extract and raffinate phases respectively because of the relatively greater quantity and percentage of solvent in the lighter phase. As disclosed in the Larner patent, the carotenes tend to concentrate in the bottoms fraction. It has been found, however, that substantial percentages of carotene are lost to the extract and that a degree of concentration of carotene in the raffinate varies considerably from one oil to another, or for the different portions of the same oil which have received various pretreatments. Further study indicates that the carotene can exist in the oil in either of two states: (1) as a complex in loose combination with protein and other material and (2) in a simpler or more or less free state. The carotene complex which is ordinarily the predominant form in raw palm oil tends to concentrate in the raffinate phase, whereas the simpler carotene complexes are lost to the extract phase. It is the object of the present invention to pretreat the oil to break down substantially all of the complex carotene so that it can be concentrated in the extract phase. It has been found possible to accomplish this object by heating the oil for a period of 10 minutes to one hour at a temperature between 200 to 500° F.

In a typical continuous process for treating palm oil in accordance with the present invention, the raw oil is flowed through a vessel or piping system in which it is heated, by steam coils, for example, for a residence time which will depend upon the temperature to which the oil is

2

heated and will vary greatly from oil to oil or even for the same oil after varying holding periods under certain storage conditions. A temperature of more than 200° F. appears to be more effective than the temperatures encountered in the ordinary paracritical fractionation itself. Temperatures over 500° F. tend to destroy valuable constituents of the oil. Temperatures within this range are usually satisfactory with the residence time required being shorter for the higher temperatures. The optimum time and temperature conditions for preheating palm oils in general can only be specified as ranges. Because of the great variation from one oil batch to another, the optimum conditions for a particular oil must be determined by testing samples. It is convenient in most cases to neutralize the oil with a mild alkali while it is undergoing heat treatment.

Immediately after the oil has been heat treated, it is intimately contacted with a relatively low boiling solvent under paracritical conditions to fractionate the oil into extract and raffinate phases. The low boiling solvent employed is usually propane, but it may be any of the liquefied normally gaseous hydrocarbons. Also, there are many other solvents which are not hydrocarbons but which are suitable for fractionating an oil under paracritical conditions. Carbon dioxide, dimethyl ether, halogenated hydrocarbons, such as dichlorodifluoromethane, may be employed. It is only necessary that the solvent be chemically inert with respect to the reactants under the conditions of the process and that the solvent have a critical temperature not higher than about 450° F., although hexane which has a critical temperature of slightly above 450° F. may be used. The reason for the critical temperature limitation is that the advantages of the so-called paracritical fractionation are attained by contacting the oil and the solvent in a temperature range near the critical temperature of the solvent in which the density of the solvent decreases rather rapidly with increasing temperature. Decreasing density is accompanied by decreasing of solubility of the oil in the solvent. This range usually extends from about 100° F. below the critical temperature to a few degrees above the critical temperature. Thus, it is relatively easy to select a temperature in the paracritical range for fractionating the oil into any desired percentage of extract and percentage of raffinate. In the concentration of carotene from the heat treated palm oil, as in the case of most paracritical fractionations, one must reach a com-

promise between recovery and concentration. For a particular heat treated palm oil a very high concentration may be obtained by fractionating at a relatively high paracritical temperature but substantial loss of carotene to the raffinate may be experienced. Fractionation at a lower paracritical temperature will reduce the carotene concentration obtained but increase the percentage of carotene recovered from the oil. The precise temperature at which fractionation will be carried out and the degree of concentration of recovery which will be sought in a particular case will be matters which are influenced primarily by market price and customary requirement considerations.

The efficiency and accuracy with which the fractionation can be accomplished are greatly increased by continuously countercurrently contacting the oil and solvent in a vertically extended fractionation zone with a solvent inlet and raffinate phase outlet near the lower end, an extract phase outlet near the upper end and an oil inlet near the middle of the zone as described in great detail in the aforementioned U. S. P. No. 2,432,021 of H. B. Larner.

I claim:

1. A method for concentrating carotene from an oil containing carotene complexes of substantially higher molecular weight than carotene, which includes the steps of: heating said oil to a temperature between 200° F. and 500° F. for a period of 10 minutes to one hour to convert said carotene complexes to carotene forms of substantially lower molecular weight; then contacting said oil with a solvent having a critical temperature less than 450° F. at temperatures in a range of temperatures near the critical temperature in which solubility decreases as temperature increases to fractionate said oil into extract and raffinate phases, said extract phase containing an

oil concentrated in carotene; and recovering from said extract phase a concentrate of carotene in a form of substantially lower molecular weight than said original carotene complexes.

5 2. A method for obtaining a concentrate of carotene from a palm oil containing substantial amounts of carotene in a complex form of substantially higher molecular weight than carotene, which method includes the steps of: heating said palm oil to a temperature between 200° F. and 500° F., for a period of 10 minutes to one hour to break complexes into carotene forms of lower molecular weight than said original carotene complexes; then contacting said oil with a 10 solvent having a critical temperature less than 450° F., at temperatures in a range of temperatures near the critical temperature of said solvent in which solubility decreases as temperature increases to fractionate said oil into a raffinate 15 phase and an extract phase containing an oil concentrated in said carotene forms of molecular weight substantially lower than said original carotene complexes; and recovering a carotene concentrate from said extract phase.

20 3. A method as described in claim 2 in which the solvent is propane.

25 4. A method as described in claim 2 in which the oil is subjected to neutralization with a mild alkali while undergoing heat treatment.
